HEADREST

Original Filed Jan. 12, 1926

Inventor
F. E. Masters,
W. A. Hussey,

By Clarence O'Brien
Attorney

UNITED STATES PATENT OFFICE.

FRANK E. MASTERS AND WILLIAM A. HUSSEY, OF TULSA, OKLAHOMA; SAID HUSSEY
ASSIGNOR TO C. A. MECHLING, OF TULSA, OKLAHOMA.

HEADREST.

Application filed January 12, 1926, Serial No. 80,776. Renewed January 3, 1927.

This invention relates to head rests and is for the use of embalmers for the purpose of securing the desired elevation of the head of the cadaver and holding the same 5 in proper position.

The primary object of the present invention is to provide a head rest for the above purpose wherein the head supporting member per se may be raised or lowered while 10 the head of the cadaver rests thereon, and without disturbing the same.

A further and important object is to provide a head rest of the before mentioned character that is relatively simple of construction, inexpensive of manufacture, and 15 efficient in use.

With the above and other objects in view as the nature of the invention will be better understood, the same comprises the novel 20 form, combination, and arrangement of parts hereinafter more fully described, shown in the accompanying drawing and claimed.

In the drawing wherein like reference 25 characters indicate corresponding parts throughout both the views:

Figure 1 is a sectional view of my improved head rest, and

Figure 2 is a side elevation of the head 30 plate or cap per se.

Now having particular reference to the drawing, our novel head rest constitutes the provision of a head supporting plate or cap 5 of metal, shaped to the contour of the base 35 of a person's head. Formed centrally upon the under side of this plate is a pair of pendent spaced ears 6—6 having aligned openings, one of which is threaded. For disposition between said ears is the upper 40 flattened end 7 of a threaded bolt 9 that is secured therebetween through the medium of a suitable screw 10.

Said threaded bolt 9 has threaded engagement within the upper interiorly threaded 45 end of a screw sleeve 11, the lower portion of the opening through which is of greater diameter than the upper interiorly threaded portion in order that a circular head 12 upon the lower end of the bolt 9 may move 50 freely therethrough, and engage the shoulder 13 thus formed within the sleeve for limiting the upward threading movement of the bolt in said screw sleeve.

The screw sleeve 11 is threaded within a sleeve 14 formed around a central opening 15 in an adjusting plate 16. The upper 55 end of the screw sleeve 11 is unthreaded as is also the upper end of the sleeve 14 for limiting the downward threaded movement of the screw sleeve 11 within the internally 60 threaded sleeve 14 of the adjusting plate 16.

The head rest is associated with the embalming table in the usual manner, and it will be apparent that when the head of the 65 cadaver is disposed upon the plate 5, a turning of the adjusting plate 16 in opposite directions will either raise or lower the head supporting plate without requiring the removal of the head from the plate.

It will also be seen that a turning of the 70 member 16 in one direction will first cause the unthreading of the bolt 9 from the screw sleeve 11. As soon as the head 12 upon the end of the bolt engages the shoulder 13, the screw sleeve will be projected outwardly 75 from the sleeve 14, and thus enable the head supporting plate 5 to be raised or lowered a distance substantially equivalent to the length of the bolt 9 and sleeve 11.

Minor changes may be made in the invention 80 without departing from the spirit or scope of the appended claims.

Having thus described the invention, what we claim as new and desire to secure by Letters Patent is:—

1. In a head rest of the character described, a plate formed with a central opening around which is an internally threaded sleeve, an externally threaded sleeve threaded within said first mentioned sleeve, and 90 being internally threaded at its upper end, a bolt threaded within the upper end of the externally threaded sleeve, means for limiting the outward threaded movement of the bolt with respect to the sleeve, and a head 95 rest carried by the upper end of the bolt.

2. In a head rest of the character described, an adjusting plate having a central opening, an internally threaded sleeve extending upwardly from the adjusting plate 100 and surrounding the opening, an externally threaded sleeve threaded in said aforementioned sleeve, the upper portion of the bore of the second sleeve being reduced to form a shoulder in the intermediate portion of the bore of said sleeve, a bolt thread- 105

ed through the reduced bore of the second sleeve and having its lower end extending into the lower portion of said externally threaded sleeve, a head rest carried by the upper end of said bolt, and a circular head formed on the lower end of the bolt and adapted for co-operation with said shoulder

for limiting the upward threaded movement of the bolt with respect to the externally threaded sleeve. 10

In testimony whereof we affix our signatures.

FRANK E. MASTERS.
WILLIAM A. HUSSEY.
